UNITED STATES PATENT OFFICE.

HERVEY ELY, OF ROCHESTER, NEW YORK, ASSIGNOR TO SAML. P. ELY.

DRYING FLOUR.

Specification of Letters Patent No. 11,046, dated June 6, 1854.

To all whom it may concern:

Be it known that I, HERVEY ELY, of the city of Rochester, county of Monroe, and State of New York, have invented an Improvement in Machines for Expelling Moisture from Flour and Meal and All Kinds of Grain.

The nature of my invention consists in the application of continuous currents of heated air to the exterior surface of revolving metallic cylinders which are closed at each end substantially in the manner shown. This heated air rising from below into the air chamber by its own levity, and at a uniform temperature, is so regulated in the manner of its introduction and discharge as to bring the contents of the cylinders to a given degree of temperature, and keep them at the same, by which arrangement the following objects are secured:

1st. A uniform degree of heat is applied to every part of the exterior surfaces of said cylinders.

2d. The contents of the cylinders are raised to a given degree of heat, and continued at the same.

3d. The flour meal or grain within the cylinders are completely protected from injury by coming in contact with foreign substances contained in the currents of heated air; particularly from becoming impregnated with smoke or gases; and also protected against scorching or burning.

4th. All waste of the dust of flour or meal, which would result from permitting currents of heated air to pass through the cylinders is entirely prevented.

5th. The flour meal or grain, as it descends, carries with it into the cylinders a sufficient quantity of cold air to absorb, as its temperature is raised, all the moisture given off by the flour &c.; and thus by its forced introduction and subsequent expansion creates a downward current through the cylinders, and out through the discharging spout with the dry flour. The air charged with the moisture given off by the flour &c. is carried off through the conveyers outside of the air chamber, without imparting itself to the heated air within the air chamber. By closing the ends of the cylinders, also, the counter current of air is excluded which would otherwise set through the cylinders from the air chamber in an opposite direction.

6th. A large saving of fuel is effected

over every other known machine by employing currents of heated air in the manner mentioned in the place of radiated heat thrown into the chamber direct, whether from an arch of masonry or a metallic surface constituting the floor of the air chamber.

To accomplish these objects I use Chilson's, or any other furnace for heating air for dwellings. Directly above the furnace I construct a chamber of brick six feet high, five feet wide, and fourteen feet long (Figure 1). The currents of heated air are introduced into the chamber by an aperture through the brick and iron floor of the same 15 inches in diameter. The admission of the air into the chamber by the furnace is regulated by a valve (Fig. 1, K). Over the aperture is laid a plate of sheet iron 2 feet wide and three feet long supported on pieces of brick five inches above the floor. The bricks are placed at regular intervals, so as to leave spaces from 6 to 10 inches wide for the transmission and diffusion of the heated air into and through the chamber. (The sheet iron plate is shown by the letter N, Fig. 1.) Within this chamber I place two revolving metallic cylinders on the plan of Tysons, or any other conveyers I may choose to adopt. Each cylinder is twelve feet long, and eighteen inches in diameter, and one is placed above the other. (A, A, Fig. 1.) These cylinders are founded on cast iron shafts $3\frac{1}{2}$ inches in diameter, and $2\frac{1}{2}$ inches at each end, and their bearings are set in the brick work at each end of the chamber. Four sets of cast iron arms are placed in the shaft with an iron hoop $\frac{1}{8}$ of an inch thick and $1\frac{1}{2}$ inches wide encircling each set of arms, and united to them. Over this frame a cylinder of the thickest tin is placed made by locking, riveting and soldering the sheets. The interior of the cylinders have a series of short tin flights soldered at regular intervals in eight lines, rising one inch from the interior surface of the cylinder, that the flour or other material may be lifted from the surface of the cylinder as it revolves (see B, B, Fig. 1). These flights are spiral at the introducing end of each cylinder, and longitudinal in the center. In setting the cylinders the receiving end is elevated six inches above the discharging end, and the material is discharged from the upper into the lower cylinder through a tin spout. The lower cylinder is

placed at a reverse angle, but with the same inclination from a horizontal line as the upper one. The material is unloaded into the upper cylinder by a tin spout, introduced 5 through the brick wall of the air chamber, and discharged from the lower by a similar spout into an elevator (I, Fig. 1,) which conveys it into a hopper boy in an upper story for cooling, from whence it descends 10 into a packing chest in order for packing. The cylinders are driven by spur wheels attached to the ends of the shafts which extend through the brick wall of the chamber. Square tin boxes inclose the ends of the 15 cylinders to prevent waste, (C, D, & E, Fig. 1, C, Fig. 3, D, Fig. 4, E, Fig. 5). These boxes have sliding doors (as shown by W, X, Y, Z, Fig. 1).

The chamber is constructed with a cast 20 iron door on each side of sufficient size to admit a man for examination of machinery and to test the temperature of the air, which should be kept from 200 to 300 degrees of Fahrenheit according to the amount 25 of work to be accomplished.

A pipe of sheet iron opens from the top 30 of the chamber to carry off moisture and air, with a valve therein to regulate the amount; a gauze wire netting is placed in the pipe to prevent the escape of flour or 35 dust. An opening is left in the wall in which a thick plate glass is inserted. Facing this glass from the inside is a thermometer to indicate the temperature.

If it should be said that this invention is 35 a simple revival of "Tysons Dryer" patented in 1831, I answer that there are marked and essential differences between

the two. The chief difference lies in the mode of applying heat. Tyson seems to 40 have relied solely upon radiated heat thrown off from a stove placed within the chamber. So far as I have been able to understand his invention this was his sole reliance. This I repudiate entirely, and depend exclusively 45 on currents of heated air introduced into the chamber direct, and from without, and so regulated by means of a valve, and by the remote location of the fire, as to prevent the possibility of scorching the flour, on the one 50 hand, or an insufficient supply of heated air on the other. The main result of drying the flour is secured by my method, in a better, safer, and more uniform manner than in the other. This method has never to my 55 knowledge been applied to the objects and purposes herein claimed.

What I claim and desire to secure by Letters Patent is—

1. Closing the cylinders, or other convey- 60 ers, at each end; or causing them to revolve in close boxes as herein described, and for the purposes set forth.

2. Applying to the exterior surface of 65 closed cylinders continuous currents of heated air, so regulated as to keep the contents of the cylinders at a given temperature by an arrangement of dampers L and N and the observation of the thermometer attached as set forth.

Rochester, N. Y., Feb. 16, 1854.

HERVEY ELY.
